H. C. WOLFE

GUM TAPE PRINTER

Original Filed April 21, 1923

UNITED STATES PATENT OFFICE.

HYMAN C. WOLFE, OF MONTREAL, QUEBEC, CANADA, ASSIGNOR TO PRINTAPE MACHINE CORPORATION, OF NEW YORK, N. Y., A CORPORATION OF NEW YORK.

GUM-TAPE PRINTER.

Application filed April 21, 1923, Serial No. 633,662. Renewed January 28, 1926.

To all whom it may concern:

Be it known that I, HYMAN C. WOLFE, a subject of the King of Great Britain, and resident of the city of Montreal, in the Province of Quebec and Dominion of Canada, have invented certain new and useful Improvements in Gum-Tape Printers, of which the following is a full, clear, and exact description.

10 This invention relates to improvements in gum tape printers and has as its object the provision of a simple, automatic printing, inking and moistening device for paper rolls for wrapping, sealing or the like.

15 In devices of this class at the present time, it is customary to have the tape printed before putting it into the machine and the cost of this printing is considerable, compared with the cost of plain gummed tape.

20 Trouble has also been experienced in these devices through the tape slackening and, when this occurs, the tape is liable to crack and twist, thus interfering with the smooth working of the apparatus.

25 In my invention, I provide a gum tape holder which is adjustable to all widths of tape or paper and which has a self inking and printing device attachment. I also provide a spring attachment to keep the tape taut and a self-damping arrangement for moistening the gummed side of the tape before using, and this operation can only be accomplished under slight pressure, thus ensuring a tape that is easily handled.

30 In the accompanying drawings;—

Fig. 1 is a side elevation of the device.

Fig. 2 is an end elevation of the tape holding device.

Fig. 3 is an end elevation of the printing arm.

40 Fig. 4 is an end elevation of the damping roller and tank.

Fig. 5 is a plan view of the apparatus.

Fig. 6 is an enlarged view of the roller locking arrangement attached to the pivoted printing arm.

45 Fig. 7 is a sectional plan view taken on the line 7—7, Figure 6.

On a base 11 is mounted an angular plate bracket 12, which is attached to the said bracket by bolts or screws. Riveted to the vertical member of the bracket 12 is a spindle 13 for supporting a gummed tape roll 14. Two screws 15 and 16 are also riveted 50 to said bracket 12 to provide adjustment and supports for two guides 17 and 18, which are drilled to suit the spindle 13 and the screws 15 and 16. Adjustment for widths of tape is made on the screws 15 and 16 by altering the position of a thumb nut 19 and a nut 20 on each screw and between which are mounted the guides 17 and 18. On the top of the bracket 12 and attached thereto by screws is a block 21 made integral with the forked bracket 22, the end 23 of which is adapted to support the printing apparatus hereinafter mentioned. A printing roller 24 mounted on a pin 25 and between the sides of a supporting link 26, which is hung from the bracket 22, is provided for printing on the tape 14 any desired instruction or design. The link 26 is held in position by the screws 28 and 29. Holes 30 and 31 are provided to adjust the printing roller to any desired height. The pin 25 is placed in the horizontal slots 32 cut in the supporting link 26. To keep the printing roller central with the gum tape, I provide the guides 34 attached to the supporting link 26 by the set screws 35. For inking the printed roller, circular ink pads 36 and 37 are placed between the sides of the links 26 and are mounted on the pins 38 and 39 respectively, which revolve in the vertical slots 40 and 41 cut in said links. To provide an easy means for detaching the inking rollers, the slots 40 and 41 communicate with horizontal slots 40^a and 41^a, so that the said rollers may be pulled clear of the supporting link without interfering with the pins 38 and 39 which may be secured to the inking rollers. Locking guides 33 slidably mounted on the printing roller support are provided to lock the inking and printing rollers in their respective working slots 40, 41 and 32. The guides are provided with vertical slots 40^b and 41^b, adapted to coincide with the slots 40 and 41 in the supporting links 26 to position the inking rollers, and vertical slots 32^a which lock the printing roller pin 25 in position. The upper end of the slots 32^a also limits the downward movement of the guides 33 by engaging with the pin 25. I also provide horizontal communicating slots 40^c and 41^c in the guides 33, which are adapted to coincide with the horizontal slots 40^a and 41^a in the support 26 when said guides are in the unlocked position, to allow the inking rollers to be easily dismantled. The bottom 55 60 65 70 75 80 85 90 95 100 105 110 115

edges 33^a of the guides are so positioned that when the guides 33 are in the unlocked position said edges are clear of the horizontal slots 25^a, thereby permitting an easy passage way for dismantling the printing roller. Spiral torsion springs 42 mounted on a pin 43 keep a constant pressure on the pin 39, which is attached to the circular ink pad 37. This pressure is transferred to the circular ink pad 36 directly below it and is thus kept in constant pressure against the circumference of the printing roller 24. The pin 43 also acts as a hinge pin for a guard 44, which covers the circular ink pads 36 and 37 and also the printing roller 24 on one side, and a guard 45 covering the circular ink pads 36 and 37 only on the other side. To hold the guards in the closed position as shown in Figures 1 and 6, a spiral torsion spring 46 is wound around the pin 43, so that the ends of the spring engage with the top of the guards and exert a pressure thereon. The spring is so positioned that when the guards are raised, the pressure on them is increased thereby ensuring the return of the guards to the closed position. To keep the printing roller against the gummed tape with pressure enough to ensure the gummed paper being printed, no matter what diameter it is, I provide the spiral torsion springs 47 wound round the set screws 48, which are in turn screwed into the forked bracket 22. One end of the spring engages with the bracket 22 and the other end engages with the pin 25, keeping the printing roller pressed against the gum tape roll 14. At one end of the base 11 is provided a cast recess to receive a tank 49, in which a roller 50 is mounted on a pin 51 and revolving in a bracket cast integral with the tank. I also provide revolving guide rollers 52 and 53 for guiding the tape 56. A cutter strip and guard 54 is also provided and fixed to the base 11 by the screws 55.

The operation of the apparatus is as follows:—When the gummed tape 56 from the

roller 14 is pulled, the roller 14 revolves and in turn revolves the printing roller 24. The ink pads ink the roller 24 which transfers 50 the inked types or cuts on to the gummed paper 14. To dampen the gummed surface of the paper, the roller 50 running in water is provided. The sharp edge of the guard 54 is provided for cutting the gummed 55 paper.

Having thus described my invention, what I claim is:—

1. A tape printing machine including a printing roller adapted to bear against a 60 roll of tape and a pair of guide arms carried by the printing mechanism and disposed upon opposite sides of the tape roll.

2. In a tape printing machine, the combination of a tape roll holder, a printing 65 mechanism including a printing roller and means for engaging said roller with a roll of tape mounted in said holder, and means carried by the roll holder for adjusting the roll to center the same with respect to the printing roller.

3. In a tape printing machine, the combination of a tape roller holder, a printing frame suspended from the top of the holder and including a pair of spaced side bars, 75 each bar being provided adjacent its lower end with a horizontal slot extending inwardly from one edge of the bar to receive the shaft of a printing roll, each bar being further provided with a pair of upper vertical slots communicating with inclined slots leading to one edge of the bar and adapted to accommodate the shafts of a pair of inking rolls, and means for locking the shafts of said rolls in said slots comprising a plate 85 slidable on each bar and provided with a pair of upper slots corresponding to the upper slots of said bar and with a lower vertical slot adapted to intersect the lower horizontal slot of the bar. 90

In witness whereof, I have hereunto set my hand.

HYMAN C. WOLFE.
